US00D798853S

(12) **United States Design Patent** (10) Patent No.: **US D798,853 S**
Park et al. (45) Date of Patent: ** *Oct. 3, 2017

(54) **MOBILE PHONE**(71) Applicant: **Samsung Electronics Co., Ltd.**, Suwon-si (KR)(72) Inventors: **Jisang Park**, Yongin-si (KR); **Kiseong Kim**, Gwangmyeong-si (KR); **Hongku Yeo**, Seongnam-si (KR); **Jin-Hoo Lee**, Seoul (KR); **Jaewoong Chung**, Seongnam-si (KR); **Duyeong Choi**, Anyang-si (KR); **Minhyouk Lee**, Seongnam-si (KR)(73) Assignee: **SAMSUNG ELECTRONICS CO., LTD.**, Suwon-si (KR)

(*) Notice: This patent is subject to a terminal disclaimer.

(**) Term: **15 Years**(21) Appl. No.: **29/585,398**(22) Filed: **Nov. 23, 2016****Related U.S. Application Data**

(63) Continuation of application No. 29/577,834, filed on Sep. 15, 2016, now Pat. No. Des. 783,567.

(30) **Foreign Application Priority Data**

Apr. 14, 2016 (KR) 30-2016-0017748

(51) **LOC (10) Cl.** ..... **14-03**(52) **U.S. Cl.**USPC ..... **D14/248**(58) **Field of Classification Search**

CLAIM

The ornamental design for a mobile phone, as shown and described.

DESCRIPTION

FIG. 1 is a top front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom front perspective view thereof; and,

FIG. 9 is a bottom rear perspective view thereof.

The broken lines in the drawings represent portions of the mobile phone that form no part of the claimed design.

FIG. 1

FIG. 2

FIG. 3

FIG. 4

FIG. 5

FIG. 6

FIG. 7

FIG. 8
